UNITED STATES PATENT OFFICE.

LÉON PONSOLE, OF ANGERS, FRANCE.

POST BASE.

Application filed August 12, 1921. Serial No. 491,816.

(GRANTED UNDER THE PROVISIONS OF THE ACT OF MARCH 3, 1921, 41 STAT. L., 1813.)

To all whom it may concern:

Be it known that I, LÉON PONSOLE, a citizen of the French Republic, and residing in Angers, Maine-et-Loire, 16 Rue de Bel-Air, France, engineer, have invented certain new and useful Improvements in and Relating to Post Bases (for which I have filed application in France, October 8, 1917, Patent No. 487,094), of which the following is a complete specification.

The invention relates to means for protecting from decay the parts or portions of posts and poles, which are near the ground and which, as is well known, is liable to rot. The invention consists of a cement foot adapted to be removably secured to the lower end of the post or pole to extend below the same and a distance above the ground in which the post or pole is planted, and which is provided with means for draining off the water which runs down the post into the foot, and also with means for permitting a circulation of air around the post or pole, whereby the life of the post or pole is greatly prolonged.

A practical embodiment of the invention is represented in the accompanying drawing forming a part of this specification, in which similar characters of reference indicate corresponding parts in all of the views.

Figure 1 is an elevation of the improvement applied;

Figure 1^a is a longitudinal section of a portion of the foot;

Figure 1^b is a transverse section of the same;

Figure 2 is an elevation of a modification;

Figure 2^a is a longitudinal section of a portion of the foot;

Figure 2^b is a transverse section of the same;

Figure 3 is an elevation of an electric iron pole;

Figure 4 is an elevation of another modification;

Figure 4^a is a longitudinal section of a portion of the foot;

Figure 4^b is a transverse section of the same;

Figure 5 is an elevation of an iron pole;

Figure 6 is an enlarged plan view partly in section, of the foot shown in Figure 1;

Figure 6^a is an elevation of a rest or support for the post;

Figure 6^b is an elevation of a washer; and 55
Figure 6^c is a modified form of washer.

Referring to Figures 1, 1^a, 1^b and 6, of the drawing the foot A is in the form of a sheath composed of two cement V-shaped members *a* and *b* having enlargements *a*², *a*³ 60 and *b*², *b*³ respectively. The enlargements *a*² and *b*² are at the upper ends of the members and *a*³, *b*³ are a short distance below the ends of the members. The enlargements are provided with apertured flanges *i* through 65 which pass bolts *k* having nuts *k*' on their ends, and by means of which the members are clamped upon the wooden post or pole B. Spring washers C are preferably arranged on the bolts *k* as shown in Figure 6 70 to prevent the nuts *k*' from working loose. The nuts *k*' are preferably round and provided with notches to permit them to be tightened or loosened by means of a tubular spanner. By thus constructing the nuts they 75 are not so likely to be removed or loosened by an unauthorized person, since a special tool is necessary for this purpose. In order to prevent any likelihood of the post slipping down in the foot, a metal bar *m* passes 80 under the lower end of the post or pole and has its hooked ends engaged with the bolts *k* between the members of the sheath or foot, as clearly shown in Figure 6.

Instead of providing the members of the 85 sheath or foot with apertured flanges, the members of the sheath are provided with a single enlargement *a*⁴, *b*⁴ and are secured to the post or pole by metallic members *c*, corresponding in shape to the members of the 90 sheath or foot and having flanged and apertured ends to receive a clamping bolt *k*², may be employed as shown in Figures 2 and 2^a. By thus constructing the foot, longitudinal passages will be formed between the 95 foot and post or pole for the free circulation of air to dry the post or pole and thereby prevent decay.

The electric iron pole C shown in Figure 3 may be provided with a shoe as shown in 100 Figure 1 or Figure 2.

The sheath or foot may be made of a single tubular member *d* with an enlargement *d*² at its upper end, as shown in Figures 4 and 4^a, and will preferably be so made for 105 posts and poles having a symmetrical shape. The sheath or foot *d* has a conical inner face, and the post or pole is given a tapering

lower end and the tapered end is so formed that spaces will be left between the pole or post and the sheath or foot, so that water running down the side of the post or pole 5 can pass down through the sheath or foot into the ground. The sheath or foot is secured to the post or pole by wedges *f* driven between the sheath or foot and post or pole. The sheath or foot is provided with a plurality of openings *p* adjacent the lower end 10 of the post or pole, so as to produce with the spaces between the wedges, a circulation of air and thereby facilitating the drying of the post or pole and preventing decay.

15 The iron pole *D* in Figure 5 is provided with a sheath or foot *d* similar to that shown in Figure 4. The sheaths or feet will preferably be reinforced by metallic bars *g* as shown in Figure 4, and it is to be understood that they may be made of any desired shape.

20 Having thus described my invention I claim:

1. A foot for posts or poles comprising a 25 tubular sheath formed intermediate its length with a tapering internal wall and with a lateral air opening above the level of the lower end of the tapering portion of the inner wall of the sheath, said sheath being 30 adapted to receive the lower end portion of

a post or pole, said post or pole resting at its lower end upon the tapering inner wall of the sheath above said lateral opening for air, and means between said post or pole and said sheath for spacing said post or pole 35 from the sheath to provide a continuous air passage extending within the sheath from the upper end of the latter to said lateral air opening.

2. A foot for posts or poles comprising a 40 tubular sheath formed intermediate its length with a tapering internal wall and with a lateral air opening above the level of the lower end of the tapering portion of the inner wall of the sheath, said sheath being 45 adapted to receive the lower end portion of a post or pole, said post or pole resting at its lower end upon the tapering inner wall of the sheath above said lateral opening for air, and an annular series of wedges inserted 50 between the inner wall of the upper end portion of the sheath and the post or pole to space said post or pole from the inner wall of the sheath from the upper end of the latter below the level of said lateral air opening.

In testimony I have hereunto set my hand at Nantes (France) this 20th day of July 1921.

LÉON PONSOLLE.
